(57) **CLAIM**

The ornamental design for a roof tile, as shown and described.

DESCRIPTION

FIG. 1 is a top perspective view of a roof tile of the present design;

FIG. 2 is a left side elevation view thereof;

FIG. 3 is a right side elevation view thereof;

FIG. 4 is an elevation view of the nose end of the roof tile;

FIG. 5 is an elevation view of the head end of the roof tile;

FIG. 6 is a top plan view of the roof tile shown in FIG. 1; and,

FIG. 7 is a bottom plan view of the roof tile shown in FIG. 1.

The broken lines shown herein are for illustrative purposes only and form no part of the claimed design.
